(57) **CLAIM**

The ornamental design for electrical wire connection terminal block, shown and described.

DESCRIPTION

FIG. 1 is a front side perspective view showing our new design for electrical wire connection terminal block;
FIG. 2 is a rear side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top view thereof; and,
FIG. 8 is a bottom view thereof.
